UNITED STATES PATENT OFFICE.

OSCAR CHARLES ROESEN, OF BROOKLYN, NEW YORK, ASSIGNOR TO WOOD NEWSPAPER MACHINERY CORPORATION, OF NEW YORK, N. Y., A CORPORATION OF VIRGINIA.

SECTIONAL TRANSFER ROLLER.

Application filed January 19, 1927. Serial No. 162,058.

This invention relates to inking mechanism, especially adapted for newspaper printing machines. The principal objects of the invention are to provide a simple and convenient way of eliminating the inking of the plate cylinder throughout a width equal to the width of one page or a multiple thereof; to provide the inking mechanism with sectional means for transferring the ink from one part of the inking mechanism to the other, which can be removed in sections so that wherever desired, of course, the inking mechanism and the whole series of rolls beyond the transfer device can be left uninked, whenever it is desired to run a web through the press less than the full width of the press; also to provide an improved form of adjusting the sectional rollers into proper relation to the adjacent rolls of the ink distributing mechanism, and especially to provide for the adjustment of the sectional rollers out away from the inking rolls with which they come in contact when transferring ink.

Other objects and advantages of the invention will appear hereinafter.

Reference is to be had to the accompanying drawings in which

Fig. 1 is an end elevation of the ink motion of a newspaper printing press, partly in section, showing a preferred embodiment of my invention applied thereto;

Fig. 2 is a side view on enlarged scale showing details of a preferred embodiment of the invention;

Fig. 3 is an end elevation of the same;

Fig. 4 is a side view of a part of the inking mechanism showing it clear across the press; and

Fig. 5 is a plan, diagrammatic in form, to show the relationship of the transfer rollers to the printed product.

Frequently in newspaper work, it is necessary to run a web of 1, 2, or 3 pages in width instead of a web of the full width. When that condition arises, it has been customary heretofore to cut off the composition from the transfer roller throughout a length of the roller equal to the width of the printing area that is not to be used. This transfer roller is located between the ink fountain and the ink motion ordinarily. If one page in width is to be omitted, a quarter of the composition of the transfer roller is cut away. This leaves a three-page printing

area. Of course in cases where only one or two pages are to be printed, additional amounts of the composition are cut away. These rollers that are cut away have to be carried in stock and whenever it is necessary to use them they have to be transferred to the press and the necessary change made to put them on. This invention is designed to avoid this keeping in stock of any mutilated rollers and also to avoid the time required for applying them to the ink motion when a narrow web is to be printed.

Referring now to the drawings, I have shown a typical ink motion. The only thing to be considered here is the method of transferring the ink from the pick-up roll to the ink drum. It is to be understood, however, that this invention can be applied at other points in the ink motion, but here it stops the transfer of ink at a point near the fountain. For the purpose of securing the above mentioned results, I provide, instead of a single transfer roller, a number of these rollers equal to the number of pages in the maximum width web to be printed and each one has a body portion of a length equal to the width of one page. They are divided up so that alternate ones are placed on opposite sides of the ink drum and pick-up roll.

Having described the general nature of the invention, I will now refer to the drawings. On each side of the pick-up roll and located in bearings on the frame of the ink motion, I provide a stationary shaft 10 fastened in proper bearings on the side frames of the inking fountains. On this shaft 10 are rigidly mounted a number of brackets 11, each one provided with two projections 12 opposite each other for receiving a pair of radial and opposite adjusting screws 13. Between the adjusting screws extends a projection 14 which is an integral part of a socket holder 15. This socket holder is mounted to turn freely on the shaft 10. By adjusting the two screws 13 at each end of the shaft 10, the transfer roller 16 is adjusted circumferentially around the shaft 10. For holding each end of the transfer roller 16, I provide a socket 17 having a threaded stem 18 which extends down into the socket holder 15 which is provided with a passage therein for the screw 18. A nut 19 is provided for adjusting the screw 18 up and down rigidly with respect to the shaft 10.

The shaft of the roller 16 is held in the socket 17 by a cover 20 which constitutes the completion of the bearing and is held in place as usual by a screw 21. The same adjustment has to be made at both ends of each of the transfer rollers 16. This provides a universal adjustment by which the rollers may be adjusted against the ink drum or the pick-up roll as may be desired. The proper pressure against the two is provided for as the screws 18 are mounted substantially tangent with respect to the pick-up roll and practically radially with respect to the ink drum. The transfer rollers project in between the surface of the two. Therefore the adjustment by the screws 18 will regulate the amount of pressure of the transfer rolls on the two surfaces with which they come in contact, the pick-up roll and the ink drum. The adjustment of the transfer rollers by means of the screws 13 is for the purpose of drawing the transfer rollers back out of contact with either one, or both of the ink drum or pick-up roll. When drawn back, the rollers 16, if desired, can be removed from their bearings by loosening up on the screws 21.

It will be seen that if it is desired to cut off one or more pages in width of the plate cylinder so as not to supply that portion thereof with ink, the proper transfer roller 16 is drawn back out of contact with the pick-up roll by means of the screws 13 and no more ink will be deposited on the ink drum throughout that area. The rest of the inking device will operate as usual. When it is desired to return the transfer roller to inking position, it is simply adjusted back by the screws 13 and the original adjustment of the screws 18 does not have to be changed ordinarily. By placing the transfer rollers 16 alternately on opposite sides of the pick-up roll, the necessary space is provided at their ends for supporting and adjusting them and these adjusting devices are thus arranged far enough apart so that the operator can get at them to perform the desired adjustments.

Although I have illustrated and described only a single form of the invention I am aware of the fact that modifications can be made therein by any person skilled in the art without departing from the scope of the invention as expressed in the claims. Therefore, I do not wish to be limited to all the details of construction herein shown and described, but what I do claim is:

1. In an inking device, the combination with the inking rolls and cylinders, of a set of rollers constituting the sole means for transferring ink through one portion of the inking mechanism, said rollers being arranged in short lengths, arranged to supply ink in a continuous strip across one of the rotary inking members when in contact

therewith and adapted to be brought into and out of contact with the rotary inking members of the inking mechanism so as to transfer the ink or not as may be desired.

2. In an inking device, the combination with the inking rolls and cylinders, of a set of rollers constituting the sole means for transferring ink through one portion of the inking mechanism, said rollers being arranged in short lengths and alternately disposed on opposite sides of one of the inking members and adapted to be brought into and out of contact therewith so as to transfer the ink or not as may be desired.

3. In an inking motion comprising a pick-up roll and an ink drum, the combination therewith, of a set of transfer rollers each one having a length equal to the width of a page as printed on the machine, each one being adapted to contact with the pick-up roll and ink drum, and means for moving each of said transfer rollers individually outwardly away from contact with the pick-up roll or ink drum to prevent the transfer of ink to a portion of the area of the ink drum.

4. In an inking mechanism, the combination with an ink drum and a pick-up roll, of a series of transfer rollers each contacting with both and each extending only a part way along the length of the same, means for adjusting each of said rollers in a direction substantially tangent to the pick-up roll and in a general radial direction with respect to the ink drum, and means for bodily moving each of said transfer rollers individually out of contact with either.

5. In an inking mechanism, the combination with an ink drum and a pick-up roll, of a series of transfer rollers each contacting with both and each extending only a part way along the length of the same, said transfer rollers being arranged alternately on opposite sides of the pick-up roll, means for adjusting each of said rollers at its two ends in a direction substantially tangent to the pick-up roll and in a general radial direction with respect to the ink drum, and means for bodily swinging each of said transfer rollers individually out of contact with both.

6. In an inking motion comprising a pick-up roll and an ink drum, the combination therewith, of a set of transfer rollers each one having a length equal to the width of a page as printed on the machine, said rollers being arranged alternately on opposite sides of the pick-up roll and each one adapted to contact with the pick-up roll and ink drum, and means for swinging each of said transfer rollers outwardly away from contact with the pick-up roll or ink drum to prevent the transfer of ink to a portion of the area of the ink drum.

7. In an inking mechanism, the combination with a pick-up roll, of a pair of sta-

tionary shafts located adjacent thereto, socket holders movably mounted on said shafts, and a socket carried by each socket holder, of a series of transfer rollers arranged end to end and having their shafts mounted in said sockets, and means for bodily moving the socket holders and transfer rollers about the stationary shafts for the purposes described.

10. 8. In an inking mechanism, the combination with a pick-up roll, of a pair of stationary shafts located adjacent thereto and parallel therewith, socket holders pivotally mounted on said shafts to swing thereabout, each socket holder having a screw arranged radially with respect to said shaft, and a socket carried by each screw, of a series of transfer rollers arranged end to end and having their shafts mounted in said sockets, whereby the transfer rollers can be adjusted radially with respect to said stationary shafts on which they are mounted, and means for bodily swinging the socket holders and transfer rollers about the stationary shafts for the purpose described.

9. In an inking mechanism, the combination with a pick-up roll, of a shaft located adjacent thereto and parallel with the axis thereof, a socket holder rotatably mounted on said shaft, a screw carried by the socket holder and arranged radially with respect to said shaft, a socket carried by the screw, a transfer roller having its shaft supported in said socket and in position to en-

gage the pick up roll and transfer the ink 35 therefrom to another part of the inking mechanism, a bracket fixed on said shaft and having a pair of opposite projections, adjusting screws extending through said projections, and a projection on the socket holder held between the ends of the screws, whereby the screws can be adjusted to turn the socket holder about the shaft away from the pick-up roll.

10. In an inking device, the combination 45 with the inking rolls and cylinders, of a set of rollers constituting the sole means for transferring ink through one portion of the inking mechanism, said rollers being arranged in short lengths and disposed on opposite sides of one of the inking members and adapted to be brought into and out of contact therewith so as to transfer the ink 50 or not as may be desired.

11. In an inking mechanism, the combination 55 with a pick-up roll, of a stationary shaft located on each side thereof, socket holders movably mounted on said shafts, and a socket carried by each socket holder, of a series of transfer rollers on opposite sides of 60 the pick-up roll having their shafts mounted in said sockets and means for bodily moving the socket holders and transfer rollers about the stationary shafts for the purpose described.

In testimony whereof I have hereunto affixed my signature.

OSCAR CHARLES ROESEN.
